UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PULLEY-STOCK.

1,280,734.

Specification of Letters Patent.

Patented Oct. 8, 1918.

Application filed March 12, 1918. Serial No. 222,021.

To all whom it may concern:

Be it known that I, ELBRIDGE R. HOLMES, a citizen of the United States, residing at Worcester, in the county of Worcester and 5 State of Massachusetts, have invented a new and useful Pulley-Stock, of which the following is a specification.

This invention relates to a pulley stock more particularly designed for use in narrow 10 ware looms. In such looms it is customary to provide a let-off weight for each separate narrow warp, which weight is suspended from a pulley mounted on a pulley stock and resting upon a slack portion of 15 the warp.

It is the object of my present invention to improve the construction of such pulley stocks, thereby securing increased economy in manufacture and more satisfactory opera- 20 tion when in use.

The preferred form of my invention is shown in the drawings, in which—

Figure 1 is a side elevation of certain parts of a narrow ware loom and showing 25 my invention in use, and

Fig. 2 is a perspective view of my im- 30 proved pulley stock.

Referring to Fig. 2, I have shown a pulley 10 rotatably secured by a stud or rivet 35 11 to a pulley stock formed from a single piece of sheet metal. The pulley stock comprises an upright portion 12 to which the pulley is secured; a reversely bent top portion 13 extending laterally substantially beyond the side edges of the pulley 10; and a 40 guard 14 extending beneath the pulley and having its outer end 15 bent upward outside of the pulley 10 and extending to a point above the lower edge of the pulley. A hook 16 extends below the guard 14 and is formed by partially severing the central portion of the guard and bending the same downward, as clearly shown in Fig. 2.

The device is shown in use in Fig. 1, in 45 which a loom frame 20 supports a warp frame 21 on which a plurality of narrow warp beams 22 are rotatably mounted. The warp W from each beam extends down-

ward around a pulley 10 mounted on one of my improved pulley stocks and then 50 passes around a series of suitable guide pulleys and rolls, as indicated in the drawing. A separate brake 23 engages each warp beam 22, one end of said brake being positioned for engagement by the top 13 of the 55 associated pulley stock.

In operation the brake beam is held by the brake while the loom gradually takes up the warp and thus raises each pulley and pulley stock with its attached weight 60 24 until the top 13 of the stock engages the brake 23. The brake is thus released, allowing the warp beam to revolve and a certain amount of warp to be let off, lowering the pulley and stock. These parts are again 65 gradually raised and the let-off operation is repeated.

The tension upon the warp may be regulated as desired by increasing or decreasing the weight 24 suspended from the hook 16 70 of each pulley stock.

This method of operation in narrow ware looms is well-known and forms no part of my invention, which resides in the specific details of construction of the pulley stock, 75 as shown in the drawings.

Attention is called to the advantages obtained by the use of the upwardly extending end portion 15 of the guard 14 which effectively prevents accidental displacement 80 of the pulley and pulley stock from its warp.

Having thus described my invention, it will be evident that changes and modifications can be made therein by those skilled in the art without departing from the spirit 85 and scope thereof as set forth in the claims, and I do not wish to be otherwise limited to the details herein disclosed, but what I claim is:

1. A pulley stock comprising an upright 90 portion to which the pulley is attached, a laterally projecting top portion, a guard extending beneath said pulley and upwardly outside of said pulley to a point above the lower edge thereof, and a hook positioned 95 below said guard.

2. A pulley stock formed of a single piece of sheet metal and comprising an upright portion to which the pulley is attached, a reversely bent top portion projecting substantially beyond the supported pulley at both sides thereof, a guard extending beneath said pulley and having an end por-

tion extending upward outside of said pulley to a point above the lower edge thereof, and a depending hook formed from the central part of said guard.

In testimony whereof I have hereunto affixed my signature.

ELBRIDGE R. HOLMES.
